US00D775943S

(12) **United States Design Patent** (10) Patent No.: **US D775,943 S**
 Quiroga De La Garza (45) Date of Patent: ** Jan. 10, 2017

(54) PACKAGE FOR TREATS

(71) Applicant: **PRODUCTORA Y COMERCIALIZADORA DE PRODUCTOS, S.A. DE C.V.**, Santa Catarina, Nuevo Leon (MX)

(72) Inventor: **Miguel Angel Quiroga De La Garza**, Nuevo Leon (MX)

(73) Assignee: **PRODUCTORA Y COMERCIALIZADORA DE PRODUCTOS, S.A. DE C.V.**, Santa Catarina, Nuevo Leon (MX)

(**) Term: **14 Years**

(21) Appl. No.: **29/507,774**

(22) Filed: **Oct. 30, 2014**

(51) LOC (10) Cl. **09-03**

(52) U.S. Cl. **D9/414**
USPC ....
